VARIFUNCTION POTENTIOMETER

Filed Sept. 19, 1949

UNITED STATES PATENT OFFICE

2,662,144

VARIFUNCTION POTENTIOMETER

Jerzy J. Wilentchik, New York, N. Y.

Application September 19, 1949, Serial No. 116,508

7 Claims. (Cl. 201—48)

1

This invention is in part a continuation of my copending application Serial No. 112,007 filed on August 24, 1949 and relates to improvements in voltage control systems comprising control means, wherein the output voltage "v" can be varied as a function of the displacement "x" of said control means according to any desirable relationship $v=f(x)$.

An object of the invention is to provide a system of one afore-mentioned character in which the output voltage function $v=f(x)$ of the instrument is composed of a desirable number of straight segments, the location, and the slope of each one of the latter being determined individually and set into the instrument in such manner that the exact profile of the desired voltage curve is obtained.

Another object of this invention is to provide means for changing the shape of the output function $v=f(x)$ easily and quickly, by unskilled operator, without dismantling the instrument and without stopping its operation.

A still further object of the invention is to provide means for accurate generation of potentials.

The invention applies to control systems, wherein the input from the control means can be expressed by a relatively large number of revolutions of the input shaft. There are known in the art non-linear resistors wound on shaped card-boards, but such an arrangement does not provide means for changing the form of the generated function.

For a better understanding of the invention, its advantages over existing art and the specific objectives attained with its use, reference should be had to the accompanying drawings and to the following specifications in which preferred embodiments of the invention have been illustrated and described.

In the drawings:

Fig. 1 is a schematic representation of the vari-function potentiometer system according to the invention.

Fig. 2 is a circuit diagram of a modified form of voltage divider according to Fig. 1.

Fig. 3 is a partial cross-section of a voltage divider according to Fig. 2.

Fig. 4 is a transverse section according to Fig. 3.

Fig. 5 is a detail view of the wiping contacts arrangement according to Figs. 2, 3 and 4.

Fig. 6 is a schematic representation of a vernier, linear potentiometer according to the invention.

Fig. 7 is a view of the intermittent motion coupling according to Fig. 6.

Referring to Fig. 1, there is shown a commutator or a tab array ring 1 of a regular circular form, the potential of each tab being controlled individually by means of a voltage divider

2

provided with a plurality of adjustable taps, its theory of operation being explained fully with reference to Figs. 3 and 4 in my amended, copending application Serial No. 112,007. The adjustment of respective taps along the length of the resistance 20 can be performed with the assistance of a voltage or resistance measuring instrument, or according to readings of a graduated scale 28 which may be imprinted along the length of pipe containing the resistance 20.

The resistance element 20 is connected across voltage supply terminals 21 and 22 and provided with adjustable taps 23a, 23b, 23c, etc. spaced along the circumference of the former and connected by intermediary of conductors 24a, 24b, 24c, etc. to respective tabs 2a, 2b, and 2c of the tab-array-ring 1. A contact device 3 operatively linked to shaft 7 and composed of two contact elements 4 and 5 insulated from each other and from the shaft 7 is adapted to be moved along the length of the tab-array-ring 1, the contact elements 4 and 5 being in physical engagement with respective tabs 2.

To eliminate the possibility of either contact element 4 or 5 being in physical engagement with two such tabs at the same time, the width of the contact elements 4 and 5 is made less than the width of a tab and less than the width of insulation between a pair of successive tabs. The distance between the elements 4 and 5 is fixed and may be preferably equal or less than the distance between the centers of two successive tabs, all tabs being of course similar to each other. The step motion may be produced through intermediary of a toothed wheel 6 sitting rigidly on shaft 7, the latter concentric to the tab-array-ring and an arm 8 coupled to shaft 9. A similar arrangement was explained and illustrated previously in my copending application Serial

No. 112,007 and a view of it is shown in Fig. 6. Upon every complete revolution of shaft 9, the arm 8 will become engaged with the toothed wheel 6 and move it a length corresponding to the tooth width of the latter. The toothed wheel 6 is designed in such a manner that upon each engagement of wheel 6 and arm 8, the contact device 3 would be moved by a distance corresponding to the distance between a pair of successive tabs, or in different words that each one of the contact elements 4 and 5 will be transferred from a respective tab to the next following one. To eliminate the possibility of a loose motion of slider 3, the shaft 7 may be provided with a detent mechanism consisting of a pointer 25 operatively linked to said shaft and adapted to engage yieldingly a notched circumference of an associated stationary disc 26, wherein the radial position of each notch corresponds to the position of a respective tab. The pointer 25

exerts a braking action upon the motion of shaft I whenever a notch is encountered.

The contact devices 4 and 5 are connected through intermediary of conductors 10 and 11 to respective terminals 12 and 13 of a resistance element 14 wound on a ring shaped core in such a manner as to form a ring of a regular circular form. A contact device 15, called generally the output contact device, is associated physically with the resistance 14, the former operatively linked to and insulated from shaft 9 and adapted to be moved by the control means 16. The control means can be a hand wheel, a servo, etc.

The operation of this system is as follows:

The potential difference between the pair of tabs $2a$ and $2b$ is distributed uniformly along the length of the resistance 14 . The pair of tabs $2a$ and $2b$ is shown associated with respective contact elements 4 and 5 . The contact device 15 while adjusted along the resistance 14 by the control means 16 will assume uniformly changing potentials depending on its position with respect to the terminals 12 and 13 . Assuming that the potential of the tab $2a$ is higher than that of the tab $2b$, and that the input from the control means tends to move the contact device 15 in a direction indicated by an arrow (from the terminal 12 along the resistance element 14 towards the terminal 13), the potential of the moved contact device will decrease uniformly between the limits fixed by respective potentials of the terminals 12 and 13 . As the contact device 15 is being transferred from the terminal 13 , towards 12 , thus terminating one complete revolution of shaft 9 , the arm 8 and the wheel 6 become engaged, which results in displacement of slider 3 by a width of a tab in the direction indicated by an arrow. The contact elements 4 and 5 are associated now with respective tabs $2b$ and $2c$. It is understood of course that the distance between the terminals 12 and 13 can be made equal to or less than the width of the contact device 15 , thus preserving the continuity of the output voltage function. As the shaft 9 is being turned in the same direction, the operation explained above would be repeated. If the input from the primary control means tended to rotate the shaft 7 in a reverse direction from the above, same explanation would still hold true, except that the arrows should be reversed.

The resistance $1/4$ should be of course of a sufficiently high resistance to allow only a negligible current flow between any two tabs and eliminate thus the effects of potential drop which may cause a considerable inaccuracy of indication.

The potential of the output contact device 15 may be applied to a suitable, high impedance amplifier and operate a motor unit and a follow up means (not shown). As a follow up means an arrangement described in Fig. 6 or any conventional, linearly wound potentiometer could be used.

Referring to Figs. 2, 3, 4 and 5, there is shown a modified form of a voltage divider which can be employed with the organization in Fig. 1. The divider 31 consists of a resistance element 42 wound uniformly on a hollow cylindrical core 34, the latter inside a concentric pipe 35 provided with plurality of longitudinal slots 36 spaced uniformly along its circumference, a plurality of selectors or contact devices 37, each contact device composed of a pair of spring leaf contact elements 38 and 39 adapted to be moved in physical engagement with said resistance, each

slot of pipe 35 serving to guide the motion of its respective contact device 37 while the surface of the pipe between slots serves to press the contact elements 38 and 39 against the resistance element 42 and improve thus the electrical contact. The pipe 35 and the core 34 are made of course of insulating material. The terminals 32 and 33 of the resistance element 42 are connected to the positive and the negative supply wires 146 and 147 respectively of a source of voltage.

The position that each selector should assume to be associated with a correct amount of resistance can be found by a resistance or voltage measuring instrument or by marking a graduated scale (not shown) along the length of each one of the respective slots 36 relative to the values of potential assumed by the contact device in that position. The handle 43 of a selector can be of course insulated from the contact elements proper, thus allowing adjustment while the unit is operating. The contact elements 38 and 39 are spaced at a such distance from each other that the voltage between them is always equal to a unit of the voltage divider scale. Assuming for example that the length of the divider resistance is ten inches and that there are one hundred scale divisions associated with the motion of the contact device 37, the distance between the two elements would be approximately 0.1 in. Assuming that the total voltage drop across the resistance 42 is one hundred voltage units, the voltage drop per division would be one unit. Similarly the voltage difference between the contact elements 38 and 39 would be one unit irrespective of position of the contact device 37. If for example, the contact device 37 has been placed opposite the scale division serial No. 47 of the divider 31, the contact elements 38 and 39 will assume respective potentials of forty-seven and forty-eight voltage units.

1015888
15 Each selector 37 is provided with a variable resistance 45 (indicated in Fig. 2 by the numerals 45a, 45b, 45c, etc.) connected across the wipers 38 and 39 via respective conductors 47 and 48, and provided with a contact wiper 46 (indicated in Fig. 2 by the numerals 46a, 46b, 46c, etc. The resistances 45 serve for vernier adjustment of potential via conductors 24a, 24b 24c, etc. applied to respective tabs 2 of the commutator ring 1 seen in Fig. 1, and can be provided with respective graduated scales to facilitate the presetting operation.

According to Figs. 1, 3 and 4, the number of slots 36 in the pipe 35 is not equal to the number of tabs 2 in the tab array ring 1. In actual equipment the number of slots and tabs will be of course the same.

The effect of current taken off by the resistances 45 can be generally compensated by proper spacing of the contacts 38 and 39 in the selector 37.

65 Referring to Fig. 6, there is shown a linear potentiometer operating on a principle similar to the principle of operation of the vari-function potentiometer.

70 It consists principally of interconnected, circular potentiometer windings 154 and 166, and of a coupling mechanism comprising a gear 159 linked operatively to shaft 157, of a displacing arm 158 coupled to shaft 156, and of a detent arm 160 cooperating with detent disc 161. The terminals 164 and 165 of the winding 166 are connected to respective voltage supply lines 146
75 and 147. The winding 166 is provided with a

pair of wiping contacts 150 and 151 linked mechanically through an insulated arm 168 to the shaft 157. The terminals 152 and 153 are connected to respective wiping contacts 150 and 151. A suitable collector ring arrangement (not shown) can be used for this purpose. Upon each complete revolution of the shaft 156 and more particularly simultaneously with a wiper contact 155 crossing the gap between the terminals 152 and 153, the arm 158 engages the gear 159 and displaces the contacts 150 and 151 by an uniform step motion. The view of the arm 158 and of the gear 159 is shown more clearly in Fig. 7. The distance between the wipers 150 and 151 is set in such a manner, that upon an assumed clockwise step displacement of the arm 168, the wiper 150 will settle relative to the winding 166 at a position occupied subsequently to the displacement by the wiper 151, and vice versa, assuming a counterclockwise displacement of the arm 168, the wiper 151 will settle at a position occupied previously by the wiper 150. Provided, that the resistance ratio of the potentiometer 154 to that of the potentiometer 166 is sufficiently high, a linearly changing voltage will be obtained at the output wiper 155. Generally, the shaft 156 is connected to a suitable control mechanism shown at 16a and the wiper 155 to an electric load circuit. The arrangement in Fig. 6 may be of course modified to serve as a vernier voltage divider with the shafts 156 and 157 being adjustable manually, independently of each other. In such a modified organization, there is no need for use of the dispacing arm 158, neither of the gear 159.

It should be borne in mind that the invention is applicable not merely to resistance elements but to all types of voltage sources comprising voltage dividing means having adjustable taps from which voltages of different magnitude, phase, frequency etc. may be obtained.

What I claim as novel, and desire to secure by Letters Patent is:

1. A functionally adjustable voltage division device comprising in combination, a pair of terminals, voltage division means connected between said pair of terminals, a plurality of contact elements disposed on said voltage division means, means to adjust said contact elements along the length of said division means between said terminals, an impedance component adapted to be connected to said elements, a third terminal, and a wiping contact device connected to said third terminal and adapted for displacement along the length of said impedance component.

2. A functionally adjustable voltage divider comprising in combination, voltage division means, a plurality of contact elements disposed on said voltage division means, means to adjust said contact elements along the full length of said division means, an impedance component, wiping contact device adapted for displacement along the length of said component, and means for connecting and disconnecting any two consecutive ones of said elements and said component in predetermined relation to the movement of said wiping contact device.

3. A functional voltage division device, comprising in combination, a single 360° arc impedance element, wiping means, control means for traversing said wiping means along the length of said element, voltage division means compris-

ing a plurality of series connected impedance sectors, intermittently actuated switching means for disconnecting one while connecting next consecutive one of said impedance sectors in shunt with said impedance element, and means to actuate said switching means in predetermined relation to the movement of said wiping means.

4. A functionally adjustable voltage divider comprising in combination, voltage division means, plurality of contact elements disposed on said voltage division means, means to adjust said contact elements along the full length of said division means in accordance with a predetermined law, a plurality of studs connected to respective ones of said elements, single impedance component, wiping contact device adapted for displacement along the length of said component, switching means for connecting and disconnecting said component and any two consecutive ones of said studs, and means to actuate said switching means in predetermined relation to the movement of said contact device.

5. In combination, a single 360° arc impedance element, wiping means, control means for traversing said wiping means along the length of said element, a plurality of studs, means to apply variable potential to respective ones of said studs, intermittently actuated switching means for connecting and disconnecting said impedance element and any two consecutive ones of said studs, and means to actuate said switching means in a predetermined relation to the movement of said wiping means.

6. In combination, a voltage division means, a plurality of contact elements disposed on said division means, means to adjust respective ones of said contact elements along the length of said division means, a plurality of studs connected to respective ones of said elements, wiping means cooperating conductively with said studs, and means to adjust said wiping means along the length of said studs.

7. In combination, voltage division means, rail means disposed around and along the length of said division means, a plurality of contact elements, interlock means between said rail means and said elements to maintain the latter to conductive engagement with said division means, said interlock means comprising a cavity in said rail means and dimensionally corresponding protuberances in said elements, said protuberances being interlocked within said cavity, and means to adjust said interlocked elements along the length of said division means.

JERZY J. WILENTCHIK.
